US00D822633S

(12) **United States Design Patent** (10) **Patent No.:** **US D822,633 S**
Yeom (45) **Date of Patent:** **** Jul. 10, 2018**

(54) **FLEXIBLE ELECTRONIC DEVICE**(71) Applicant: **LENOVO (BEIJING) CO., LTD.**,
Beijing (CN)(72) Inventor: **Jihun Yeom**, Beijing (CN)(73) Assignee: **LENOVO (BEIJING) CO., LTD.**,
Beijing (CN)(***) Term: **15 Years**(21) Appl. No.: **29/629,644**(22) Filed: **Dec. 14, 2017**(30) **Foreign Application Priority Data**

Nov. 4, 2015 (CN) 2015 3 0435882

(51) **LOC (11) Cl.** ..... **14-03**(52) **U.S. Cl.**USPC ..... **D14/138 AB**; D14/138 G; D14/341(58) **Field of Classification Search**USPC .... D14/138 AA, 138 AB, 138 AC, 138 AD,

Primary Examiner — Jeffrey D Asch*Assistant Examiner* — Tracey J Bell(74) *Attorney, Agent, or Firm* — Oppedahl Patent Law
Firm LLC(57) **CLAIM**The ornamental design for a flexible electronic device, as
shown and described.**DESCRIPTION**FIG. 1 is a perspective view of a flexible electronic device
showing the new design;

FIG. 2 is a front view thereof;

FIG. 3 is a back view thereof;

FIG. 4 is a left side view thereof;

FIG. 5 is a right side view thereof;

FIG. 6 is a top view thereof; and

FIG. 7 is a bottom view thereof.

FIG. 8 is a perspective view of the flexible electronic device
shown in a first bending position; and

FIG. 9 is a front view of FIG. 8.

FIG. 10 is a perspective view of the flexible electronic device
shown in a second bending position; and,

FIG. 11 is a front view of FIG. 10.
